UNITED STATES PATENT OFFICE.

MAX SCHONBRUNN, OF NEW YORK, N. Y.

COMBINATION-SPRING-TOOL HOLDER.

1,252,040.

Specification of Letters Patent.

Patented Jan. 1, 1918.

Application filed June 21, 1917. Serial No. 176,071.

To all whom it may concern:

Be it known that I, MAX SCHONBRUNN, a subject of the King of Hungary, first naturalization papers obtained, and a resident of 5 the city of New York, borough of Manhattan, in the county and State of New York, have invented a new and Improved Combination-Spring-Tool Holder, of which the following is a full, clear, and exact description.

This invention relates to lathe tool holders, and more particularly to a combination spring tool, and the invention has for its general objects to improve the construction 15 and operation of devices of this character so as to be reliable and efficient in use, comparatively inexpensive to manufacture, and so designed as to permit of a large variety of operations with only one holder and in- 20 terchangeable cutter or tool-carrying posts.

A more specific object of the invention is the provision of a lathe tool holder which is provided with an offset shank formed with a vertical opening in which is removably 25 or reversibly clamped a vertical spring post which carries the cutter.

With such objects in view, and others which will appear as the description proceeds, the invention comprises various novel 30 features of construction and arrangement of parts which will be set forth with particularity in the following description and claim appended hereto.

In the accompanying drawing, which 35 illustrates certain embodiments of the invention and wherein similar characters of reference indicate corresponding parts in all the views,

Figure 1 is a side view of the combination 40 tool, with portions in section to illustrate the details of construction;

Fig. 2 is a horizontal section on the line 2—2, Fig. 1;

Fig. 3 is a side view showing a different 45 form of post;

Fig. 4 is a detail view showing a post with another form of cutter;

Fig. 5 is a plan view of the cutter shown in Fig. 4; and

Fig. 6 is a view showing a thinner post 50 held by a split bushing in the holder.

Referring to the drawing, A designates the holder and B the cutter-carrying post. The holder A is formed with a body or shank 1 from which rises at one end an inclined neck 2 that terminates in a forwardly projecting horizontal head 3. This head is provided with a vertical opening 4, in which the post B is disposed, such post being adjustable vertically or rotatably in the head 60 3, in which it is held by a clamping bolt 5 disposed in a transverse opening 6. This bolt has a notch 7 of the same radius as the opening 4, so that the notch can receive the post B. The post B may have provision at 65 each end for holding cutters or tools 8 and 9, as shown in Figs. 1 and 4, and is reversibly mounted. The post B' in Fig. 3 is a modification adapted for holding other kinds of cutters, and in both instances the posts can 70 be adjusted to produce the desired spring effect. If more resiliency is required a post B² of smaller diameter may be employed, and in this case a split bushing 10 is inserted in the passage 4, so as to tightly clamp the 75 post B² in the head 3. Obviously, other cutters than those shown may be employed, and a variety of posts may be designed for special cutters, but only a single holder will suffice.

From the foregoing description taken in connection with the accompanying drawing, the advantages of the construction and method of operation will be readily understood by those skilled in the art to which 85 the invention appertains, and while I have described the principle of operation together with the device which I now consider to be the best embodiment thereof, I desire to have it understood that the device 90 shown is merely illustrative and that such changes may be made when desired as fall within the scope of the appended claim.

Having thus described my invention, I claim as new and desire to secure by Letters 95 Patent:

A tool comprising a holder formed of a bar-like shank having an upwardly for-

wardly inclined neck integral with one end of the shank, and a head on the neck extending horizontally therefrom in a direction away from the shank and located wholly above the latter, there being a passage in the head at right-angles to the length of the shank, and a spring cutter-carrying post in

the form of a single-piece resilient rod clamped in the said passage of the head and having means for supporting a cutter in line with the shank while the portion of the post between the cutter and the head is free to swing.

MAX SCHONBRUNN.
